LEAD POT FURNACE

Chester M. MacChesney, Chicago, Ill., assignor
to Acme Steel Company, Chicago, Ill., a corpora-
tion of Illinois

Application May 31, 1945, Serial No. 596,890

12 Claims. (Cl. 263—47)

I

This invention relates to improvements in lead pot furnaces which are commonly used for annealing or cleaning strip metal or the like by running the strip material endwise through baths of molten lead, and the primary purpose of the invention is to provide an improved segmental lead pot adapted to be used in such a furnace for increasing the capacity and speed of operation thereof.

In a lead pot furnace, the molten metal is contained in a comparatively shallow pot formed usually of cast iron, steel or semisteel and the strip material is moved endwise by power means and depressed between some of its supports sufficiently to permit it to be progressively immersed in the hot metal during its travel. The lead pot is heated by burning gases or the like to the required temperature, a high temperature being employed for annealing purposes and a lower temperature when the molten lead is employed only for removing oil and dirt from the strip metal. In either case, the lead pot is very highly heated in order to maintain the lead in a hot molten condition and has to be of very substantial length to allow the strip metal to remain in the bath for a suitable interval of time. When the pot is of great length, its manufacture gives rise to molding and casting problems and when in use it expands unduly and is likely to warp and lose its shape so that it has to be discarded after limited use. This limitation upon the size or length of the lead pot has imposed a corresponding limitation upon the capacity and speed of operation of the furnace since the strip metal has to remain in the molten bath for a substantial period in order to accomplish the desired results. With the length of the pot thus limited, it has been necessary to move the strip metal through the bath at a relatively low speed in order to permit successive portions of the strip to remain submerged in the bath for the necessary interval of time, thus restricting the output of the furnace.

The principal object of the present invention is to provide an improved furnace, of the type referred to, having a lead pot made up of a plurality of connected segments or sections, each of which may be cast in one unit, thus permitting the composite length of the pot to be increased to any desired extent, within the limits of practical operation, and allowing a corresponding increase in the speed of movement of the metal strip and the output of the furnace. Another important object is to provide a lead pot for molten metal comprising metal sections connected together by a joint which causes a portion of the

2

molten metal at the joint to solidify and form a seal between the sections. A further object is to provide a lead pot for furnaces comprising a plurality of cast metal sections, the adjacent sections being connected by an intervening flexible unit or section which is capable of compensating for expansion and contraction of the cast metal parts. Still another object of the invention is to provide a lead pot of the type referred to which comprises a pair of cast metal sections having outwardly turned flanges which are clamped to corresponding flanges of an intervening connecting section, formed preferably of resilient flexible material, such as sheet steel or the like. Another object of the invention is to provide a lead pot comprising spaced cast metal sections and an intervening connecting section which is connected thereto by joints which are made fluid tight by solidified portions of the bath metal contained in the pot. Another object of the invention is to provide a lead pot furnace comprising a furnace structure formed in two or more units which are spaced apart, each unit supporting a section of a segmental cast metal lead pot, the sections of the lead pot being provided on their adjacent ends with means for establishing a connection with an intervening section which is formed of steel or the like and therefore capable of yielding to compensate for the expansion and contraction of the cast metal sections, the intervening section being located in the space between adjacent furnace units so that it is not subjected to the direct action of the heat of the furnaces, the sections being connected by joints made fluid tight by solidified portions of the molten bath in the unheated region between the furnace units. Other objects of the invention relate to various features of construction and arrangement which will appear more fully hereinafter.

The nature of the invention will be understood from the following specification taken with the accompanying drawings in which two embodiments of the invention are illustrated. In the drawings,

Fig. 1 shows a side elevation of one form of lead pot furnace embodying the features of the present invention;

Fig. 2 shows an enlarged top plan view of the furnace illustrated in Fig. 1 with parts thereof broken away;

Fig. 3 shows a longitudinal vertical axial section through the furnace on the line 3—3 of Fig. 2;

Fig. 4 shows an enlarged transverse vertical

section taken on the line 4—4 of Fig. 3 with the lead pot shown in elevation;

Fig. 5 shows a vertical section taken on the line 5—5 of Fig. 3, the parts of the furnace behind the nearer portions of the lead pot being removed; and

Fig. 6 shows a side elevation of a modified form of lead pot embodying the present invention which may be employed in the type of furnace illustrated in Fig. 1.

As illustrated in Figs. 1 to 5, inclusive, of the drawings, the invention is embodied in a furnace 10 mounted upon a concrete floor or other support 11 and comprising two similar and separate furnace units 12 which are spaced apart to form an intervening space or chamber 13 in which a connection is made to the adjacent ends of two cast metal lead pot sections 14 by means of an intervening connecting section 15 which is formed preferably of steel plates or the like. The lead pot sections 14 are preferably formed of cast iron or other material capable of withstanding the high temperature of the molten lead or other material which forms the bath 16 contained within the composite lead pot made up of the sections 14 and 15. As shown in Fig. 3, a metal strip 17 is adapted to be moved through the bath in the direction of the arrow 18, being passed under an arcuate guide member 19 located at the left-hand or inlet end of the lead pot and beneath a roller 20 mounted on a support 21 at the discharge end of the lead pot. The guide 19 and the support 21 may be carried by an overhead supporting structure, not illustrated, which does not form a part of the present invention.

The furnace units 12 are carried by I-beams 23 which extend transversely of the furnace with their lower flanges resting upon the floor or other support 11 and each furnace unit comprises a flat metal plate 24 which rests upon the upper flanges of the I-beams 23 and which supports the outer shell 25 of the furnace unit which is made up of a bottom wall 25^a, side walls 25^b, an outer end wall 25^c, and an inner end wall 25^d, thus providing a hollow vessel of rectangular cross section which is supported at its outer end by upwardly extending I-beams 26 having their lower ends resting upon a longitudinal extension 24^a of the bottom plate 24 of that furnace unit. The extension 24^a of the bottom plate is supported by short longitudinal I-beams 27 which rest upon the floor or foundation 11 and the supporting posts 26 are reinforced by triangular brace members 28 which are attached to the outer flanges of the member 26 and to the extension 24^a of the plate. The top ends of the I-beams 26 at the outer end of each furnace unit are connected by an angle bar 29 which is welded or otherwise secured thereto. The bottom ends of the I-beams 26 are secured to the base plates 24 by other angle bars 30.

At the sides of the furnace, the outer walls 25 are supported by vertical I-beams 31 which rest at their lower ends upon the bottom plate 24, this plate being extended at the sides of the furnace as shown at 24^b where it is supported by the projecting ends of the transverse horizontal I-beams 23. Other triangular brace members 32 are connected to the upright members 30 and to the lateral extensions 24^b of each base plate 24, thus rigidly supporting the furnace walls in a lateral direction.

At the inner end of each furnace unit 12, the end wall 25^d is supported by an upright metal plate 33 which is attached to the adjacent bot-

tom wall 24 by an angle bar 34. These furnace walls 25^d and the plates 33 are recessed on their upper sides to conform to the transverse under surface contour of the lead pot sections 14 and, adjacent these recesses, the end plates 33 are provided with angle bar brackets 35 which carry supports 36 of refractory material of the proper shape to conform to the lower surface contours of the lead pot sections 14.

The walls of the furnace shells 35 may be formed of brick or other material adapted to withstand relatively high temperatures and the walls of these outer shells are lined with firebrick or other refractory material adapted to withstand the very high heat which is created in the furnace for the purpose of maintaining the lead or other material forming the bath 16 in a molten condition and at the desired temperature. As illustrated, the bottom wall 25^a of each shell is protected by a floor or lining 39 made up of a number of parts which are separated by transversely extending division or bridge walls 40 formed of firebrick or the like and provided at their tops with cast metal caps 41 constructed as inverted channel-shaped members which embrace portions of the uppermost bricks of the bridge walls 40. These channel-shaped members 41 extend beyond the ends of the walls 40 into the side wall linings of the furnace hereinafter described, and their top surfaces lie in one plane so that they serve as supports for the cast metal lead pot sections 14. These walls 40 are mounted directly upon the bottom plates 24 of the furnace sections and the bottom walls 25^a of the furnace shells are divided by these bridge walls as the bottom lining 39 is thus divided. One of the bridge walls 40 lies in direct contact with the inner end wall 25^d of the outer shell of each section, thus forming a refractory protection therefor, and the outer walls 25^c of the furnace shells are protected by inner linings 42 and 43 formed of firebrick or other refractory material. The lining portions 42 terminate short of the end portions of the lead pot sections 14 but the lining portions 43 extend upwardly and terminate flush with the upper surfaces of the outer end walls 25^c of the outer shells.

The outer side walls 25^b of the furnace shells are protected by linings 44 formed of firebrick or other refractory material which extend upwardly from the bottom wall 25^a to the plane of the upper edges of the side walls 25^b, as shown in Fig. 4. The upper edges of the outer walls 25^b and 25^c of the furnace shells and the adjacent upper edges of the linings 43 and 44 are protected by a firebrick ledge 45 which projects over the inner edges of the linings 43 and 44, thus defining a rectangular opening 46 through which the lead pot sections 14 may be lowered to the positions where they rest upon the upper surfaces of the bridge walls 40. The firebrick ledges 45 are held in place by metal plates 47 which are attached to the angle bars 29 at the ends of the furnace and to other angle bars 49 which extend along the sides of the furnace where they are secured to the upper ends of the I-beams 31. At the middle of the furnace, the firebrick ledges 45 and the cover plates 47 are arched upwardly as shown at 45^a and 47^a, respectively, in Fig. 3, to accommodate the intermediate lead pot section 15, the lateral edges of which extend upwardly above the level of the top edges of the cast metal lead pot sections 14.

The division walls or bridge walls 40 which extend transversely of the furnace units form a plurality of combustion or heating chambers 50

the clamps are located in the space 13 between the two furnace units 12, the material of the bath 16 is not maintained in a highly fluid condition in the outwardly extending recesses 61 between the vertical flanges 15^a and the portions of the flanges 14^a which flare upwardly and outwardly therefrom, so that some of the lead or other material of the bath solidifies in the crevasses between the two flanges 14^a and 15^a and forms a more or less thin layer or gasket which provides a fluidtight joint for the body portion of the bath which lies above it and is in liquid condition. The outwardly flaring flanges serve not only to provide convenient means for permitting adjacent sections to be clamped together but also as heat dissipating means for causing the solidification of the metal located between them, the flanges being of sufficient area for this purpose.

By locating the intermediate connecting section 15, the outwardly flaring flanges and the clamps 60 in the space 13 between the two furnace units 12, the solidification of portions of the bath metal to form fluidtight joints is facilitated and another advantage is gained in that the intermediate resilient metal section 15 is not directly heated by the action of any of the combustion chambers 50 and is therefore capable of withstanding the temperature to which it is subjected, namely, that of the molten metal or the like which forms the bath 16. The steel plates or the like of which the intermediate section is formed are therefore able to retain their temper and resiliency after continued use and are adapted to yield sufficiently to compensate for any relative endwise movement of the two lead pot sections 14 which may take place in response to temperature changes therein. The clamps 60 may also be continued in use for long periods without deterioration inasmuch as they are located in the space 13 and contact only with those portions of the flanges of the lead pot sections which are removed from direct contact with the molten bath.

In Fig. 6 of the drawings, there is shown a modified form of lead pot comprising a middle section 63, two end sections 64, and two intermediate sections 65, illustrating the possibility of extending the length of the lead pot still further by employing a greater number of sections which may be mounted within a furnace similar to that previously described except that it would comprise three separate furnace units instead of two and the connections between the middle section 63 and the end sections 64 would be located in the spaces between these separate furnace units. Each end section 64 is constructed in the manner of the sections 14 previously described and comprises at its inner end an outwardly directed flange 64^a. The middle section 63 is formed from cast iron or the like, like the sections 64, and is provided at each end with an outwardly directed flange 63^a similar to the flange 14^a heretofore described. The two flanges 63^a and 64^a are connected by an intermediate member 65 which is identical in construction with the member 15 previously described, having outwardly directed parallel plates or flanges 65^a which contact with the flanges 63^a and 64^a of the adjacent sections 63 and 64, respectively, being secured thereto by clamps 66 which are identical in construction with the clamps 60.

It will be apparent that, by means of the present invention, a lead pot furnace has been provided in which the length of the lead pot may

be extended to any desired degree in order to permit the traveling metal strip to remain submerged in the molten metal or the like for the necessary interval of time even though its speed of travel be greatly increased as compared with the previous commercial practice. With the use of this invention, it is therefore possible to effect a great increase in the speed of treatment of strip metal and the resulting output of the furnace without any decrease of the quality of the product produced.

Although certain forms of the invention have been shown and described by way of illustration, it will be understood that it may be constructed in various other embodiments which come within the scope of the appended claims. In the appended claims the flanges on the lead pot sections are defined as extending "outwardly" in the sense that they extend away from the longitudinal axis of the lead pot. Although the receptacle for the molten metal is referred to in the claims as a "lead pot" it will be understood that this term is used broadly and is intended to include within its scope a pot which may contain any molten metal or other liquid capable of being used for treating the strip material passing therethrough.

I claim:

1. In a furnace, a lead pot comprising cast metal sections, and an intervening flexible section secured thereto.
2. In a furnace, a lead pot comprising cast metal sections having outwardly turned flanges on their adjacent ends, a yielding section interposed between said first named sections and having flanges contacting with said first named flanges, and means for securing said contacting flanges together.
3. In a furnace, a lead pot comprising cast metal sections having outwardly turned flanges on their adjacent ends, a yielding section interposed between said first named sections and having flanges contacting with said first named flanges, and a series of clamps embracing each pair of contacting flanges for securing them together.
4. In a furnace, a plurality of upwardly concaved cast metal lead pot sections having outwardly directed flanges on their adjacent ends, and an intervening upwardly concaved sheet metal section having outwardly directed end flanges secured to said first named flanges.
5. In a furnace, a refractory furnace structure formed in a plurality of units spaced apart, a lead pot comprising a plurality of sections each carried by one of said units, and a yielding section interposed between and connected to adjacent ones of said first named sections in a space between two of said units.
6. In a furnace, a refractory furnace structure formed in a pair of units spaced apart, an upwardly concaved cast metal lead pot section carried by each of said units, means in said units for heating said lead pot sections, said sections being provided on their adjacent ends with outwardly turned flanges, an upwardly concaved sheet metal section interposed between said first named sections in the space between said units and having outwardly turned flanges which contact with said first named flanges, and a series of clamps embracing each pair of contacting flanges.
7. A furnace comprising a lead pot formed in sections, and means for securing said sections together to form a receptacle for a molten bath metal, said sections being formed to provide

which communicate with each other through openings 40^a formed in the bridge walls by omitting some of the firebricks of which these walls are constructed. These chambers 50 serve as combustion chambers for combustible gas discharged from the burners 51 which have their casings mounted in the outer side walls 25^b of the furnace shells and which have their nozzles 51^a located in refractory tubular members 52 extending through the outer walls 25^b and through the side linings 44, as shown particularly in Figs. 2 and 4. Adjacent the right-hand or discharge end of the furnace, as viewed in Figs. 1, 2 and 3, the burners 51 are of smaller capacity than those burners which are located in the middle portion and adjacent the inlet end of the furnace, since less heat will be required to maintain the temperature of the contents of the lead pots near the discharge end of the furnace where the moving strip 17 will have been heated by its previous contact with the molten bath. Gas for maintaining the operation of the burners 51 is supplied through pipes 53 and 54 which extend along the outer sides and ends of the furnace walls and which are connected with a suitable source of supply beneath the floor 11 as indicated by dotted lines in Fig. 2. The flow of gas through these pipes to the individual burners is controlled by a series of valves 55, one of which is provided for each burner, and those burners which heat the inner ends of the furnace units 12 are connected to the supply pipes 53 while those burners which heat the outer end portions of the lead pots 14 are supplied with gas through the separate pipes 54, thus permitting an independent operation of the different groups of burners and the supply of different gases thereto if desired.

The bottom walls of the combustion chambers 50 are formed by the various sections of the bottom refractory linings 39 and these lining sections are inclined transversely of the furnace as shown in Fig. 4, the upper surface of each lining section being located at one end just below the outlet of one of the burners 51 while at the other end each lining section 39 is located flush with the bottom surface of an opening 56 which extends through the adjacent side lining 44 and through the outer side wall 25^b. These openings permit the ash to be cleaned out of the combustion chambers at intervals and they are normally closed by doors 57 which are pivoted on metal tubes 58 mounted in those parts of the openings 56 which lie within the walls 25^b. The doors 57 are hinged at their upper edges and normally remain closed due to the action of gravity.

The lining sections 39 are inclined in opposite directions in adjacent combustion chambers 50 and the burners 51 are located at opposite ends of these adjacent combustion chambers. Thus, the burners 51 along one side of the furnace units are staggered with respect to those along the other side of the furnace and burners at each side of the furnace open only into alternate combustion chambers. In this way, a substantially uniform or other desired distribution of the heat may be brought about throughout the interior chamber of each furnace unit and the gases of combustion are permitted to pass freely from one combustion chamber to another so that there is a free distribution of the hot gases throughout the areas of the under sides of the lead pot sections 14.

Each lead pot section 14 is cast in one piece and is concave in cross section with the middle portion of its bottom wall 14^a substantially flat 75

and with the side walls 14^b curving upwardly therefrom. At the outer end of the section, the end wall 14^c curves upwardly. The top edges of the side and outer end walls of the lead pot sections 14 terminate slightly below the plane of the lower surface of the ledge 45, as shown in Figs. 3 and 4. The bottom wall of each lead pot section 14 is increased in thickness to form a downwardly extending projection having a flat surface 14^d which is adapted to rest upon the upper surfaces of the channel-shaped members 41 which form the top members of the bridge walls 40, as heretofore described. The lead pot sections are held by gravity on these members 41 and are adapted to be moved into and out of the furnace chamber by means of a traveling crane or the like. For this purpose, the side walls 14^b of the lead pot are provided at spaced intervals on each side of the vessel with integrally formed lugs 14^e having upwardly directed recesses 14^f therein which are adapted to be engaged by the hooks of the crane. At its inner end, the bottom and side walls of each lead pot section 14 are flared outwardly away from the path of travel of the metal section 17, that is, the bottom wall 14^a is flared downwardly and the side walls 14^b are flared laterally, thus forming a continuous outwardly directed flange 14^g, the edge of which lies in a plane extending transversely to the longitudinal axis of the furnace. These outwardly flared portions 14^g of the two lead pot sections are located in a space or chamber 13 between the two furnace sections 12 and also between portions of the side walls 25^b which are continuous between the two furnace units. These outwardly directed flanges 14^g of the sections 14 are united with each other by the intervening connecting section 15 heretofore referred to.

The intervening section 15 is formed preferably of steel plates or the like having sufficient flexibility and resiliency to permit them to yield in response to changes in temperature and to return to their normal positions by virtue of their resiliency. For this purpose, the member 15 comprises a central upwardly concave channel-shaped member 15^a having its top wall 15^b directed upwardly and having its side walls 15^c directed downwardly and welded or otherwise suitably secured to the top edges of plates or flanges 15^d which form the ends of the section 15 and which extend downwardly and outwardly parallel to each other, as shown in Figs. 3 and 5, with their outer portions contacting with the inner surfaces of the outer parts of the flanges 14^g of the sections 14. The upper surface of the top wall 15^b of the channel is located substantially in alignment or slightly above the top surfaces of the bottom walls 14^a of the sections 14 so that the concavity of the section 15 forms with the concavities of the sections 14 a continuous chamber for containing the bath 16 through which the metal strip 17 travels.

Each side flange 15^d of the intermediate section 15 is secured to one of the flanges 14^g of a section 14 by means of a series of clamps 60 each of which comprises a heavy U-shaped frame member 60^a, adapted to embrace the coacting edges of the flanges 14^g and 15^d, and a clamping screw 60^b engaging one of the arms of the frame member and contacting with the outer surface of the adjacent flange 14^g for the purpose of clamping the two contacting flanges securely together. These clamps 60 are spaced apart at intervals throughout the extent of the flanges 14^g and 15^d, as shown in Fig. 5, and, inasmuch as

crevices at the joint between said sections whereby the joint is rendered fluidtight by solidified portions of said bath in said crevices.

8. In a furnace, a lead pot comprising metal sections provided on their contiguous ends with outwardly flaring flanges, and means for securing said flanges together to form a receptacle for a bath of molten metal, said flanges being formed to receive portions of said metal between them and to solidify said portions to form a sealing gasket between said flanges.

9. In a furnace, a lead pot adapted to contain a bath of molten metal and comprising metal sections provided at their contiguous ends with outwardly directed flanges adapted to receive a portion of said metal between them, and means for securing said flanges together, said flanges being constructed to provide sufficient heat dissipating surface to effect the solidification of said portion of said metal between them.

10. In a furnace, a lead pot comprising metal sections provided on their contiguous ends with outwardly flaring flanges, means for securing said flanges together to form a receptacle for a bath of molten metal, said flanges being formed to receive portions of said metal between them and to solidify said portions to form a sealing gasket between said flanges, and means for applying external heat to the major portions of said sections, the parts of said sections at and adjacent said flanges being unheated except by said bath.

11. In a furnace, a refractory furnace structure formed in a plurality of units spaced apart,

cast metal lead pot sections each carried by one of said units, means in said units for applying external heat to said lead pot sections, and means in the space between said units for connecting said sections to form with said sections a receptacle for a molten metal bath, said connecting means comprising parts adapted to effect the solidification of a portion of said bath to provide a sealing gasket between said sections, said space between said units being unheated except by said bath.

12. In a furnace, a lead pot comprising cast metal sections having outwardly turned flanges on their adjacent ends, a yielding section interposed between said first named sections and having flanges contacting said first named flanges, and means for securing said flanges together, fluidtight joints between the contacting flanges being formed by solidified portions of the molten bath contained in said pot.

CHESTER M. MACCHESNEY.
